(57) **CLAIM**

The ornamental design for an electric vehicle front, as shown and described.

DESCRIPTION

FIG. 1 is a bottom, front, and left side perspective view of our new design for an electric vehicle front, showing an illustration of use on an electric vehicle;

FIG. 2 is another bottom, front, and left side perspective view thereof, with the exemplary electric vehicle removed for clarity of details;

FIG. 3 is a top, rear, and right side perspective view thereof; FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines shown in the drawings are for the purpose of illustrating environmental subject matter and portions of the article that form no part of the claimed design. The shading lines shown in the drawings represent the approximate three-dimensional contour of the design, and are not intended to indicate surface decoration. The broken lines and unshaded surfaces are included to identify parts of the article's appearance that form no part of the claimed design.

1 Claim, 9 Drawing Sheets
